GARMENT

Elsie Swan, Los Angeles, Calif.

Application July 20, 1938, Serial No. 220,245

4 Claims. (Cl. 2—115)

This invention relates to a garment, and especially to one adapted to be used on the upper part of the body, as for example a shirt.

More particularly, this invention obviates the necessity of any fastening means such as buttons or ties. In this way, the donning and shedding of the garment are both facilitated, and yet there is an assurance that the garment fits properly.

It is one of the objects of this invention to provide a garment of this character.

It is another object of the invention to provide a shirt of the "sport" variety that is inexpensive to manufacture and that presents a pleasing appearance, and good fit.

These objects are attained by using a special pattern for defining the shoulder and neck portions. Accordingly it is another object of this invention to make it possible to use a pattern for a garment of the character specified, and that ensures proper fit around the neck and shoulder portions.

The proper fit of any garment at these regions is perhaps the most difficult to obtain. However, the pattern herein described renders such fit easy to obtain. This is in part due to the choice of goods used and to the direction of the threads of the fabric where it embraces the shoulders.

This invention possesses many other advantages, and has other objects which may be made more easily apparent from a consideration of one embodiment of the invention. For this purpose there is shown a form in the drawing accompanying and forming part of the present specification. This form will now be described in detail, illustrating the general principles of the invention; but it is to be understood that this detailed description is not to be taken in a limiting sense, since the scope of this invention is best defined by the appended claims.

Referring to the drawing:

Figure 1 is a pictorial view of the garment shown in use on a wearer;

Fig. 2 is a view similar to Fig. 1, showing the manner in which the neck opening may be opened up to facilitate donning or shedding the garment, and to make it possible to pull the garment over the head of the wearer; and

Fig. 3 is a diagram illustrating the pattern of the fabric member which is utilized to form the neck and shoulder portions of the garment.

The shirt embodying the invention is shown as having a top fabric portion 1, the developed view of which is seen in Fig. 3. This fabric member 1 is shown as having a "turn-down" collar 2,

defining a neck opening. Extending from the wing portions of the collar 2 are the members 3 and 4, which are adapted to overlie the chest of the wearer and to extend diagonally downwardly along the upper front of the shirt. These members 3 and 4 have respectively edges 5 and 6 forming a V where these edges meet after the members 3 and 4 are folded down along the upper front portion of the shirt. Thus for example the edge 5 of member 3 is shown as being in line with the lower edge 7 of the member 4; and similarly the edge 6 of the member 4 lies along the line of the lower edge 8 of member 3. The overlapping portions of members 3 and 4 are thus defined between the lines or edges 9 and 10 which cross at the neck opening and diverge downwardly. These overlapping portions of members 3 and 4 are not joined elsewhere except along the edges 7 and 8, where the member 1 is joined to the lower front portion 11 of the garment. The edges 12 and 13 form the top of the shoulders. The back of the garment 11 may be attached to these edges.

In order to fold the pattern illustrated in Fig. 3 to conform with the garment illustrated in Fig. 1, the left hand member 3 is folded downwardly and inwardly and the right hand member 4 is also folded downwardly and inwardly. These two members 3 and 4 are lifted so as to bring the shoulder edges 12 and 13 substantially on a level with each other.

If it should be desired to put sleeves such as 14 and 15, upon the garment, these sleeves may be attached to the edges 16 and 17 of the member 2, and to corresponding edges of the back of the garment.

The overlapping defined by the edges 9 and 10 is of such an amount that the collar 2 and the neck opening remain close to the neck of the wearer, unless the neck opening be purposely expanded as illustrated in Fig. 2. Under such circumstances the garment may be put on or off by passing the head through the enlarged neck opening. However, due to the particular manner in which the threads of the fabric making up the member 2 are run, these threads are diagonal to the shoulder edges 12 and 13. The direction of the threads is indicated by the cross lines 18 in Fig. 3. Accordingly, the fabric is permitted to give to overlie the shoulder areas of the wearer and to accommodate itself to these areas. The result is that the garment fits well.

The materials available for the fabric 2 are, of course, dependent upon the judgment of the manufacturer. For sports wear, heavier cloths,

such as flannels or woolens, may be used. This type of fabric is especially adaptable, for the threads have sufficient resiliency or spring to provide a good fit without the necessity of careful tailoring. Also, there is a tendency of goods of this character to urge the neck band around the neck of the wearer. In this way the necessity of any fasteners, such as buttons or the like, is entirely obviated, and the garment is simple and inexpensive to manufacture.

What is claimed is:

1. In a garment adapted to cover the upper part of the body, and adapted to provide a neck opening, in which garment fastening devices adjacent to the neck are obviated, and which can be donned by pulling the garment over the head of the wearer, a fabric member forming the neck opening as well as the shoulder portions, said member being adapted to be placed around the neck of the wearer, and having front portions extending diagonally downwardly from the shoulders and overlapping below the neck opening, the overlap being defined by edges of the fabric member diverging downwardly from the neck, the overlap being limited to the central front portion of the garment and extending downwardly to a place considerably above the waist region, the overlapping parts being joined together only at the bottom edges thereof, and a waist covering member joined to the bottom edges of the fabric member.

2. In a garment adapted to cover the upper part of the body, and adapted to provide a neck opening, in which garment fastening devices adjacent to the neck are obviated, and which can be donned by pulling the garment over the head of the wearer, a fabric member forming the neck opening as well as the shoulder portions, said member being adapted to be placed around the neck of the wearer, and having front portions extending diagonally downwardly from the shoulders and overlapping below the neck opening, the overlap being defined by edges of the fabric member diverging downwardly from the neck, the overlap being limited to the central front portion of the garment and extending downwardly to a place considerably above the waist portion, the bottom edge of each overlapping portion being formed by upwardly diverging parts extending toward opposite sides of the garment.

the lowermost portion of each of said edges being substantially central of the garment, the overlapping parts being joined together only at the bottom edge thereof, and a waist covering member joined to the bottom edges of the fabric member.

3. In a garment adapted to cover the upper part of the body, and adapted to provide a neck opening, in which garment fastening devices adjacent the neck are obviated, and which can be donned by pulling the garment over the head of the wearer, a fabric member forming the neck opening as well as the shoulder portions, said member being adapted to be placed around the neck of the wearer, and having front portions extending diagonally downwardly from the shoulders and overlapping below the neck opening, the overlap being defined by edges of the fabric member diverging downwardly from the neck, said fabric member being in one piece and having threads in the front of the garment that run diagonally toward the shoulders, the overlapping portions extending downwardly to a place considerably above the waist region, the overlapping parts being joined together only at the bottom edges thereof, and a waist covering member joined to the bottom edges of the fabric member.

4. In a garment adapted to cover the upper part of the body, and adapted to provide a neck opening, in which garment fastening devices adjacent the neck are obviated, and which can be donned by pulling the garment over the head of the wearer, a fabric member forming the neck opening as well as the shoulder portions, said member being adapted to be placed around the neck of the wearer, and having front portions extending diagonally downwardly from the shoulders and overlapping below the neck opening, the overlap being defined by edges of the fabric member diverging downwardly from the neck, said fabric member being in one piece and having threads in the front of the garment that run diagonally toward the shoulders, the overlap being limited to the central front portion of the garment and extending downwardly to a place considerably above the waist region, the overlapping parts being joined together only at the bottom edges thereof, and a waist covering member joined to the bottom edges of the fabric member
